M. L. CLELAND

LUGGAGE CARRIER

Filed April 15, 1926

UNITED STATES PATENT OFFICE.

MELVIN L. CLELAND, OF HASTINGS, NEBRASKA, ASSIGNOR TO G. A. ROTH MANUFACTURING COMPANY, OF HASTINGS, NEBRASKA, A CORPORATION.

LUGGAGE CARRIER.

Application filed April 15, 1926. Serial No. 102,275.

The present invention relates to luggage carriers, and has for its object to provide a device of this character which can be readily applied to the running board of an automobile or other vehicle and embodies novel features of construction, whereby it can be easily and effectively locked in either an extended position or a collapsed position.

Further objects of the invention are to provide a device of this character which is simple and inexpensive in its construction, which enables the parts to be compactly folded into position at the edge of the running board when not in use, and which provides effective means for locking the parts in extended position.

While one particular form of the invention is shown and described in this application for illustrative purposes it will be understood that many modifications and changes can be made in the details of construction without departing from the spirit of the invention.

For a full understanding of the invention reference is to be had to the following description and accompanying drawings, in which,

Figure 1 is a side elevation of a luggage carrier which is constructed in accordance with the invention, showing the same as extended and in position for use.

Figure 2 is a side elevation of the same device showing it in a collapsed position.

Figure 3 is a top plan view of the device when folded.

Figure 4 is a transverse sectional view of the device when folded, taken on the line 4-4 of Figure 2.

Figure 5 is a transverse sectional view on the line 5-5 of Figure 2, looking in the direction of the arrows.

Corresponding and like parts are referred to in the following description and indicated on all of the views of the drawing by like reference characters.

Referring to the drawings, the numeral 1 designates a lower horizontal bar which is adapted to be secured to the running board of an automobile. This lower bar 1 is pivotally connected by means of a series of parallel links 2 to an upper bar 3 which is adapted to be moved toward and away from the lower bar, but is always held in a parallel relation thereto by means of the links 2. The bars 1 and 3 preferably have

an angle iron formation and are reversely disposed with respect to each other, so that when they are brought together, as shown by Figures 4 and 5, they cooperate with each other to form a substantially rectangular housing within which the links 2 are received. The luggage carrier thus presents a neat appearance and has a smooth outer side.

The lower bar 1 may be secured to the running board of an automobile, such as the one indicated by dotted lines on Figure 1, in any suitable manner. As shown on the drawings, it is provided with a pair of U-shaped brackets 4 which are secured in place by means of rivets 5. The arms of the brackets receive the edge of the running board between the same, the lower arms having clamping screws 6 threaded therein. The upper ends of the clamping screws may have heads 7 swiveled thereon for engagement with the bottom of the running board, while the lower ends of the clamping screws are provided with suitable handles 8.

A locking brace bar 9 is pivotally connected at 10 with one end of the lower bar 1, the swinging end of the locking bar being formed with a laterally projecting stud 11, which is adapted to interlock with a key-hole slot 12 in the end of the upper bar 3 when the luggage carrier is in an extended position.

The stud 11 has a reduced or shank portion 11^a which is adapted to be moved into the contracted end of the key-hole slot 12 after the head of the stud has been inserted through the large end of the key-hole slot. A cam lever 13 is pivotally mounted on the upper bar 3 and arranged for engagement with the projecting end of the stud 11 to lock the stud in the contracted end of the key-hole slot. The cam lever is arranged on the outer side of the upper bar 3, being pivoted thereon at 14 and provided with a finger piece 13^a, by means of which it can be manipulated. When the stud 11 is locked in engagement with the key-hole slot by means of the cam lever 14, the device is held securely in an extended position. It may also be noted that the locking bar 9 then performs the additional function of providing an extension at one end of the luggage carrier.

When it is desired to collapse the luggage carrier the cam lever 13 is swung into in-

operative position and the lateral stud 11 disengaged from the key-hole slot 12. The upper bar 3 may then be swung downwardly against the lower bar 1 with the links 2 housed within the elongated space provided between the two angle iron bars. The locking bar 9 is pivotally connected to the side of the lower bar 1 which is adjacent the edge of the running board, and when the device 10 is collapsed the locking bar is swung downwardly on the outside of the lower bar 1, being received in the space between the said lower bar and the edge of the running board. As shown more clearly by Figure 15 4, a washer 15 is interposed between the adjacent U-shaped bracket 4 and the lower bar 1, said washer surrounding the rivet 5 and spacing the U-shaped bracket from the lower bar so that the lower edge portion 20 of the locking bar may be received between the bar 1 and the bracket 4. The upper edge of the bar 1 is formed with a notch 16 which is suitably arranged to receive the lateral stud 11 when the locking bar is swung downwardly, thereby enabling the major portion 25 of the locking bar to be effectively housed in the space between the lower bar 1 and the edge of the running board. The locking bar may be formed with a slight lateral bend 30 to fit around the washer 15.

Applied to the upper bar 3, preferably at an intermediate point in the length thereof, is a latch member 17. This latch member extends downwardly below the upper bar 3 35 and is adapted to spring over the edge of the flange on the lower bar 1, as indicated by Figures 4 and 5 to lock the parts in a collapsed position, after the latch becomes disengaged from the lower bar 1 when the upper bar is forcibly moved upwardly.

Having thus described my invention what I claim as new and desire to secure by Letters Patent of the United States is:

1. A luggage carrier including an upper bar, a lower bar, links connecting the bars and pivotally attached thereto to admit of the upper bar being moved toward and away from the lower bar, a locking bar pivotally connected to the lower bar, a lateral stud 45 in the swinging end of the locking bar, the upper bar being formed with a keyhole slot adapted to detachably receive the stud, means for locking the stud in engagement with the contracted end of the key-hole slot to hold the parts in an extended position, the locking bar being adapted to be swung downwardly along side of the lower bar when the parts are collapsed and the lower bar being formed with a notch to receive the 50 stud.

2. A luggage carrier including an upper bar, a lower bar, links connecting the bars and pivotally attached thereto to admit of the upper bar being moved toward and away 55 from the lower bar, a locking bar pivotally

connected to the lower bar, a lateral stud on the swinging end of the locking bar adapted to detachably engage the upper bar to lock the parts in an extended position, a clamping bracket applied to the lower bar for 70 engaging the running board of an automobile, and means for spacing the clamping bracket from the lower bar, the locking bar being adapted to be swung downwardly along side of the lower bar and received in 75 the space between the lower bar and clamping bracket when the device is collapsed, the lower bar being formed with a notch to receive the lateral stud of the locking bar.

3. A luggage carrier including a pair of 80 bars, links connecting the bars and pivotally attached thereto to admit of the bars being moved toward or away from each other, one of the bars having an opening therein, a locking rod pivoted to the other bar and provided with a stud adapted to enter the opening, and cam means for locking the stud in engagement with the opening.

4. A luggage carrier including a pair of 90 bars, links connecting the bars and pivotally attached thereto to admit of the bars being moved toward or away from each other, one of the bars being provided with an opening having a reduced end, a locking rod pivotally connected to the other bar and formed 95 with a lateral stud adapted to be inserted through the opening and having a shank adapted to be moved into the reduced end of the slot, and means for holding the stud in an interlocking engagement with the reduced end of the slot.

5. A luggage carrier including a pair of 100 bars, links connecting the bars and pivotally attached thereto to admit of the bars being moved toward or away from each other, one 105 of the bars being formed with a slot having a reduced end, a locking rod pivotally connected to the other bar and formed with a stud adapted to be inserted through the slot, said stud having a shank portion which can be moved into the reduced end of the slot, and a locking member permanently mounted upon the bar and adapted to engage the stud to hold the shank thereof in the reduced end of the slot.

6. A luggage carrier including a pair of 110 bars, links connecting the bars and pivotally attached thereto to admit of the bars being moved toward or away from each other, one of the bars being formed with an opening having a reduced end, a locking rod pivotally connected to the other bar and provided 115 with a stud adapted to be inserted through the opening, said stud having a neck which can be moved into the reduced end of the opening, and a cam member pivotally mounted on the bar for engagement with the stud to hold the shank thereof in the reduced end of the opening.

7. A luggage carrier including a pair of 120

bars, links connecting the bars and pivotally attached thereto to admit of the bars being moved toward or away from each other, clamping brackets for one of the bars, a 5 fastening member securing the brackets to the bars, a keeper associated with one of the brackets and secured to the bar by the same fastening member, a locking rod connected to the other bar, and means for detachably

connecting the locking rod to the first mentioned bar to hold the luggage carrier in extended position, said locking rod being foldable against the first mentioned bar and adapted to be engaged by the before mentioned keeper to lock the carrier in a collapsed condition. 10

In testimony whereof I affix my signature.
MELVIN L. CLELAND.
